UNITED STATES PATENT OFFICE.

SMITH CHARLES PULLMAN, OF CATSKILL, NEW YORK.

ALARM FOR RAILWAY-TRAINS.

SPECIFICATION forming part of Letters Patent No. 315,662, dated April 14, 1885.

Application filed October 18, 1884. (No model.)

To all whom it may concern:

Be it known that I, SMITH C. PULLMAN, a citizen of the United States, residing at Catskill, in the county of Greene and State of New York, have invented a new and useful Improvement in Electric Alarms for Railway-Trains, of which the following is a specification, reference being had to the accompanying drawings.

10 My invention relates to electric alarms for railroad-trains, designed to signal to the engineer when a car breaks loose from a train, or to enable the conductor to signal to the engineer from either car of a train, as will be 15 hereinafter fully described, and particularly pointed out in the claims.

In the drawings, Figure 1 is a sectional detail view of a locomotive, tender, and one car of a train, showing an application of my signaling apparatus thereto; and Fig. 2 is an end elevation of a passenger-coach with the apparatus applied. Fig. 3 is an enlarged detail view of one of the spring-jacks, and Fig. 4 is a side elevation of one of the jacks with 25 one side plate removed.

Referring by letter to the accompanying drawings, A designates the locomotive, which is provided with the battery B and the vibrating bell C.

30 D designates a switch by which the circuit may be opened when the engineer does not desire to hear the bell ring. The line-wires are insulated and wrapped together for convenience and neatness, and are run along the side 35 of the car, where they are out of the way and out of sight. At each end of each car are provided the binding-posts E E', which connect the line-wires and the push-buttons F. From the binding-posts the line-wires extend 40 through openings G in the ends of the car over the door far enough to permit them to be coupled with the wires of the next cars. The projecting ends of the line-wires are connected to my improved coupling-jacks to 45 form the circuit; and I will now describe the construction of my coupling-jacks. The body portion H and two sides, I I', of the jacks are of hard rubber. The seats J for the binding- 50 posts J' are of brass, separated by the hard rubber. The body portion H of the coupling-

jacks is concave on each side near its forward end, and is then convexed until it forms the point I'. To each side of the body portion H is secured a German-silver spring, J², which is bent to conform to the outline of the 55 forward portion of the body H. The springs J and the sides I I' are secured in place by screws. The coupling-jacks are all alike in construction, so that the coupling can be effected at either end of the car. The cable 60 consists of two wires incased in lead, and run from the engine under the tank to its rear end. On the coaches the wires are covered with gutta-percha. When two jacks are shoved together, the hard rubber separates 65 the springs and makes two separate conductors. When the train breaks apart, the jacks pull apart, and the springs come together and close the circuit, which causes the vibrating bell on the engine to ring, and notifies the 70 engineer that his train has parted. If the engineer does not want to hear the bell ringing until he has coupled up again, he can turn the crank of the two-point switch on the dead-pin, which opens the circuit, thus stopping 75 the bell. The jack on the rear end of the rear car can be shoved astride the cord to keep it open.

Having thus fully described my invention, what I claim as new, and desire to secure by 80 Letters Patent of the United States, is—

1. The jack having the non-conducting body provided with the forwardly-extending reduced projection having the wedge-shaped point, springs made of conducting material 85 and secured to the body on opposite sides, the front ends of the springs extending beyond the wedge-shaped point, said extended portions of the springs being bent in the form of a compound curve and adapted to come 90 together normally at their front ends to close the circuit, and conducting-wires attached to the springs, substantially as described.

2. The combination of the jacks having each the conducting body provided with the forwardly-extending reduced projection having the wedge-shaped point, springs made of conducting material and secured to the body on opposite sides, the front ends of the springs extending beyond the wedge-shaped point, 100

said extended portions of the springs being bent in the form of a compound curve, and adapted to come together at their ends when the jacks are disconnected, the conducting 5 wires or cables, the battery, and push-buttons, substantially as described.

In testimony that I claim the foregoing as

my own I have hereto affixed my signature in presence of two witnesses.

SMITH CHARLES PULLMAN.
